Primary Examiner — Lauren R Calve(74) *Attorney, Agent, or Firm* — Global Intellectual Property Agency, LLC; Daniel Boudwin(57) **CLAIM**

The ornamental design for a wardrobe clothes hanger, as shown and described.

DESCRIPTION

FIG. 1 is a perspective view of a wardrobe clothes hanger; FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The shade lines in the Figures show contour and not surface ornamentation.

The broken lines shown in the drawings represent environmental effects or potential embodiments and do not form any part of the claimed design.

The claim is shown with a symbolic break in its length. The appearance of any portion of the article between the break lines forms no part of the claimed design.
